UNITED STATES PATENT OFFICE

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS

PENCIL

Application filed November 5, 1930. Serial No. 493,502.

This invention relates in general to mechanical pencils having a lead propelling means actuated by relative rotation between the body and a part fitted to one end thereof. 5 It may be employed to advantage with a tip for the pencil, and the description to follow will deal with such a unit, the features embodied in its construction, and the means cooperating therewith for its connection with 10 the pencil body.

The particular improvements with which this invention is concerned have to do with the construction of the tip and a central guide tube which is mounted axially therewithin; 15 the connection between the tip and the pencil body which is axially recessed for the accommodation of certain operating parts; and the means by which the tip is assured of smooth rotation relative to the body, of a secure frictional connection therewith, and of 20 stability against deflection laterally thereof. These and other objects, as will hereinafter appear, are fully set forth in the accompanying drawings, in which—

25 Figure 1 is a longitudinal section through a pencil in which is embodied the improvements of this invention;

20 Figs. 2 and 3 are enlarged transverse sections taken, respectively, on lines 2 and 3 of Fig. 1;

Fig. 4 is a view in perspective of a friction lining which may be anchored within the body adjacent its lower end;

25 Figs. 5 and 6 are similar views of friction linings having slightly modified constructions;

Fig. 7 is a longitudinal section through a pencil tip and proximate body end, showing a modification in the construction of these 30 parts;

Fig. 8 is an enlarged detail in section of the tip and body end to which it is connected, showing the construction which is illustrated in Fig. 7; and

45 Fig. 9 is an enlarged transverse section taken on line 9 of Fig. 7.

As a practical embodiment of the invention, I have illustrated in the accompanying drawings a pencil having a body A which 50 desirably may be made of composition ma-

terial adapted to be formed to shape under the influence of heat and pressure. Such a body is ordinarily produced from two complementary halves, as indicated by the sections *x* and *y* in Figs. 2 and 3. The upper 55 end of the body may be formed with a chamber for spare leads closed by an eraser mounting as shown.

Extending axially for a substantial distance in the lower portion of the body is a 60 chamber 10 which extends through to its lower end. This chamber is of a non-round cross section, as indicated in Fig. 2, so as to cooperate with the flattened head 11 of a screw-threaded propeller 12 when the latter is moved longitudinally in response to a force produced by turning of a complementary screw-threaded part. In this manner the propeller is permitted to travel lengthwise of itself while remaining non-rotative.

The body walls surrounding the chamber near its lower end are desirably recessed to accommodate a friction lining 14 of which three forms are suggested in Figs. 4, 5, and 6. In the construction shown in Figs. 1 and 4, the 75 lining walls at its upper end are slotted out at 15, the displaced material in the form of a ribbon being turned around to provide hooks or eyes 16 through which the material forming the body is flowed in the process of fusing 80 the two halves thereof. The lining just referred to provides a mechanical bond between the body sections so as to prevent their accidental separation in case of an imperfect union. The lining is furthermore so placed 85 relative to the end of the body as to extend slightly therebeyond, the protruded lining end being slotted as at 17 to provide a plurality of arcuate sections or jaws 18 which may spring radially to a limited extent.

In the construction of Fig. 5 the eyes 16 of the friction lining are produced by ribbons cut from the slots 17 at the lower end, instead of the opposite end, as shown in Fig. 4. These eyes are adapted to be anchored within the 95 material forming the body and serve to mechanically connect the sections thereof, the same as already described. In Fig. 6, I have shown a lining which is tubular throughout that portion of its length which is fitted with- 100

in the body, the outer lining end 19 which protrudes below the body end being irregularly but symmetrically formed in some such manner as therein shown. By having three or more sides which approach the axis of the lining more closely than the connecting angles, I take advantage of the spring properties of the walls so formed to engage frictionally with an internally fitted part, as will presently be described.

For purposes of appearance, the outer surface of the pencil body near its lower end may be recessed annularly as at 20 so as to accommodate in flush relation with the remainder of its surface the upper end of a hollow tip B which is fitted over and upon the body. The walls of the tip may be inclined as at 21 from a point of minimum diameter adjacent the writing end to a point near its opposite end 20 where the walls are straightened out cylindrically as at 22. The body end upon which the tip is fitted besides being recessed slightly, as already noted, may also be tapered somewhat as at 23 to conform to the size and shape of the tip walls. With the parts so constructed the tip is adapted to be fitted upon the body end with the interior faces of its walls in the upper region closely approaching the proximate walls of the body (see Fig. 8). The top edge of the tip may abut an annular shoulder 24 formed by the recessing of its surface, and when so positioned assures a co-relationship between the walls of the tip and body as above indicated. This is desirable as affording a means by which to resist any lateral pressure tending to deflect the tip out of axial alignment with the body.

The tip may desirably be made of metal having its walls drawn or otherwise produced to the desired size and shape. At its lower end, the tip walls are slotted at two or more places 25 to provide spring sections for gripping a lead C that is fed through the tip. This lead is supported by a guide tube 26 having a mounting in the lower region of the tip and extending axially therefrom to fit within the friction lining of the body. To support and secure the tube within the tip, the walls of the latter may be somewhat thickened in its lower region, as at 27, by an excess of material which is disposed upon its interior surface. In the region of this thickened wall portion, the tip is formed with an inner cylindrical surface 28 forming a seat wherein may be fitted the lower end of the guide tube. To retain the tube fixedly within the seat, one or more indentations 29 in the walls of the tip may be formed with a punch or prick, these indentations being transferred into the walls of the tube whereby to lock the one inseparably and non-rotatably to the other. By the construction described, the tube is both secured and steadied in axial relation with the tip.

The internal diameter of the tube is such

as to freely receive the lead C, and also the threaded propeller 12 which is adapted to travel longitudinally therewithin. At its upper end the tube walls, slightly constricted as at 30, are provided with internal threads which coact with the propeller. Externally the walls of the tube are engaged by the spring fingers 18 of the friction lining. A sufficient friction is maintained upon the body by these spring fingers to retain the tip securely in place upon the body end.

In operation a lead is expelled through the tip by advance of the propeller consequent upon rotation of the tip relative to the body. With exhaustion of the lead, the tip, together with the propeller, may be withdrawn from the body by the application of a force sufficient to overcome the frictional gripping of the spring fingers with the guide tube. In this operation the propeller comes out with the tip and may be unscrewed therefrom to permit insertion of a new lead, or the latter, if desired, may be introduced through the writing end of the tip. Thereafter the tip may be replaced upon the body end, the spring fingers again taking hold of the guide tube to retain the tip in place.

It is possible to modify the construction somewhat and yet make use of the features of improvement herein disclosed. An example of such an alternative construction is set forth in Figs. 7, 8 and 9. In this construction the body adjacent its shoulder 24 may be slotted diametrically as at 35, providing on opposite sides thereof sections of the body which have capacity for slight springing movement toward or from each other. In this construction no friction lining is shown although it may optionally be employed. The tip walls engage directly with the lower body end, the sections whereof are compressible, as required, to accommodate the tip. In this construction there may be sufficient friction maintained to sustain the tip in place. The tip may be rotated freely as necessary for advancement of the propeller, and may also upon the application of sufficient force, be disengaged from the body whose split end serves normally to hold the tip in place. In this embodiment of the invention, the guide tube is supported within a mounting which is formed by a cylindrical inner surface of the tip produced by straightening a section 36 of its walls intermediately of other inclined sections. By this means I obtain the same result as with the thickened wall construction shown in Fig. 1. Also, above the upper end of the guide tube, I may arrange within the body chamber 10 a lining 37 in the form of a narrow channel open along one side 38 with opposite bulges 39 accommodating between them the propeller 12 whose head is receivable lengthwise of the channel, as shown best in Fig. 9. By this construction I utilize flat stock which is bent

to the required channel form to furnish a lining interiorly of the pencil body whereby to assure a correct and perfect slideway for the propeller and its head. Such a lining can be produced at much less expense than if formed from a tube, and dispenses with the necessity of providing a special non-round form of body chamber clear from end to end, such as may cooperate directly with the propeller head in the manner already described.

This invention is advantageous in several respects. The construction is more simplified, its parts may be assembled with facility, and the manner of their securement is very dependable. In addition, the point at which frictional connection is made with the tip is well down toward its writing end—considerably below the top edge of the tip which may abut the body shoulder to resist deflection from true axial position. For these reasons stability of the tip at all times is assured.

I claim:

1. A pencil comprising a body having an axial opening, a lead guide tube receivable within said opening, means for propelling a lead in the guide tube, and resilient means carried by the body for securing the tube in the opening.

2. A pencil comprising a body having an axial opening, a lead guide tube receivable within the opening, means for propelling leads in the guide tube, resilient means carried by the body for securing said tube in the opening, and a tip carried by the tube.

3. A pencil in which is included a body having an axial chamber open at one end with a lining fitted partly within the chamber, the lining end protruded from the chamber being formed to yield radially under pressure, and an operating unit for the pencil in the form of a hollow tip having an axial lead guide tube adapted to receive pressure from the protruded end of the lining when entered therewithin in consequence of the tip being applied to the chambered end of the pencil body.

4. A pencil having a body one end of which is formed with an axial chamber wherein is a lining slotted to provide radially movable spring sections, a tube closely fitted within the lining and frictionally engaged by the spring sections thereof, and a tip joined to the tube and connected thereby to the pencil body.

5. A pencil having a body one end of which is formed with an axial chamber wherein is a lining protruding in part beyond the body end at which point it is slotted to provide spring jaws, and a hollow tip mounting a tube receivable within the lining to be frictionally engaged by the jaws, the tip when applied to the body providing an enclosed space wherein the jaws are disposed.

6. A pencil comprising a body having a longitudinal opening, a lead guide tube

adapted to enter therein, a lining in said opening and having jaws extending beyond said opening for frictionally engaging said tube to retain it in the body, and a tip having a cylindrical inner portion engaging an end of said tube to secure the tube and tip together.

7. A pencil comprising a body having a longitudinal opening, a lead guide tube adapted to enter therein, a lining in said opening and having jaws extending beyond said opening for frictionally engaging said tube to retain it in the body, a tip having a cylindrical inner portion engaging an end of said tube to secure the tube and tip together, said tip being conical in part and registering with a frusto-conical portion of the end of said body.

8. A pencil having a body to one end of which is applied an operating unit in the form of a tapered tip having one portion of its walls extended cylindrically to provide a bearing of substantial length wherein is immovably mounted a lead guide tube deriving axial support solely from its frictional engagement with the cylindrical tip walls, and means cooperating with the body and tube for propelling a lead through the tip.

9. A pencil having a body axially chambered at one end and provided with a tubular lining therein, an operating unit for the pencil in the form of a hollow tip mounting an axial lead guide tube telescopically received within the lining to derive bearing therefrom, and means disposed exteriorly of the body chamber within the hollow of the tip providing a spring engagement between the lining and tube whereby to support the tip rotatably, but releasably, in place upon the body end.

10. A pencil having a body axially chambered at one end and provided with a tubular lining therein, an operating unit for the pencil in the form of a hollow tip mounting an axial lead guide tube telescopically received within the lining to derive bearing therefrom, and spring means extended from the lining to a point exteriorly of the body chamber and within the confines of the tip exerting a lateral pressure against the tube whereby to support the tip rotatably, but releasably, in place upon the body end.

11. A pencil having a body one end of which is axially chambered to receive therein a lead guide tube axially extended from and joined to a tapered tip adapted to be fitted upon and over the chambered body end, the walls of the tip adjacent its larger end being spaced from the tube, and radially movable spring means associated with the body adjacent its chambered end and disposed within the space interiorly of the tip in frictional engagement with the tube, the spring means serving to connect the tip removably and rotatably with the body.

12. A pencil having a body to one end of which is applied an operating unit in the form of a hollow tapered tip having one portion of its walls internally extended cylindrically to provide a bearing of substantial length wherein is fitted a cylindrical lead guide tube deriving axial support from its mounting within the cylindrical wall portion of the tip, and means cooperating with the body and tip for propelling a lead through the tip.

13. A pencil having a body to one end of which is applied an operating unit in the form of a hollow tapered tip having one portion of its walls internally extended cylindrically to provide a bearing of substantial length wherein is fitted a cylindrical lead guide tube deriving axial support from its mounting within the cylindrical wall portion of the tip, there being an indentation in the tip wall extending also into the tube wall to lock the one inseparably and non-rotatably to the other, and means cooperating with the body and tip for propelling a lead through the tip.

14. A pencil having an axially chambered body to one end of which is applied an operating unit in the form of a hollow tapered tip mounting a lead guide tube the wall of which for a limited distance lies adjacent that of the tip wherein is formed an indentation extending also into the tube wall to lock the one inseparably and non-rotatably to the other, and means extending into the body chamber cooperating with the body and tube for propelling a lead through the tip.

15. A pencil having an axially chambered body to one end of which is telescopically fitted an operating unit in the form of a hollow tapered tip having its walls coaxing circumferentially with the pencil body to limit the movement of one upon the other, a guide tube mounted axially in the tube and extended therefrom in progressively spaced relation to its walls for fitting within the body chamber, means carried by the body and disposed within the tip between its walls and the guide tube therewithin in frictional engagement with the latter to releasably connect the tip to the body, the tip being rotatable thereupon, and means cooperating with the body and tip for propelling a lead through the tip.

JOHN P. LYNN.
